UNITED STATES PATENT OFFICE.

JOHN P. REILLY, OF ST. LOUIS, MISSOURI, ASSIGNOR OF ONE-FOURTH TO EUGENE
MCBRIDE, OF ST. LOUIS, MISSOURI.

DETACHABLE SHOE-HEEL LIFT.

Application filed December 13, 1920. Serial No. 430,166.

To all whom it may concern:

Be it known that I, JOHN P. REILLY, a citizen of the United States, and resident of the city of St. Louis, and State of Missouri, have invented certain new and useful Improvements in Detachable Shoe-Heel Lifts, of which the following is a specification, containing a full, clear, and exact description, reference being had to the accompanying drawings, forming a part hereof.

My invention relates to improvements in detachable shoe heel lifts and has for its primary object a cheap and effective attachment whereby the lift may be readily applied or removed, as desired.

A further object is to construct a lift of rubber in which is imbedded edgewise a fabric provided with anchor holes to prevent slipping.

20 In the drawings:

Fig. 1 is a view of the inside face of a shoe heel lift having my fastening devices applied thereto.

Fig. 2 is a plan view of the outside or 25 wearing surface of the lift.

Fig. 3 is a side view of my improvement.

Fig. 4 is a rear view of the same.

Fig. 5 is a plan view with the parts 30 broken away, illustrating the fabric member molded in the lift for re-enforcing the same and preventing slipping.

Fig. 6 is a side view of the heel portion of the shoe with parts broken away having my invention applied thereto.

35 Fig. 7 is a perspective view of one of the fasteners which I employ.

Referring to the drawings, 8 indicates the permanent portion of the shoe heel, 9 the detachable lift. The detachable lift 40 may be formed of any material, but is preferably formed of rubber. Imbedded in the rubber and extending entirely around the same, as illustrated in Fig. 2, is a strip of fabric 10, which is provided with a series 45 of holes 11 in which the rubber may pass during the molding operation and which may be aptly termed "anchor holes" for the fabric. The strip 10 is molded edgewise in the lift and an edge thereof acts as a 50 wearing surface and also prevents slipping and it also has a tendency to strengthen the lift when formed of rubber.

It will be observed that this strip of fabric extends practically throughout the 55 length and width of the lift and terminates

in the loops 11^a, which also increases the traction at the rear portion of the lift. By this construction a considerable more amount of fabric surface is disposed along the rear tread surface of the heel. Imbedded in the forward edge of the lift are spaced apart hook members 12 of rather peculiar construction and are composed of two prongs 13 and 14, the prong 13 being larger than the prong 14 and is imbedded 60 and molded in the lift. The prong 13 is provided with anchor holes 15. The prongs 13 and 14 of the fastener are connected by the portion 16, which is curved to fit the forward edge of the lift. The prong 14 65 is sharpened, as at 17 so that it may be easily driven into the permanent portion of the heel. As previously pointed out, the fasteners 12 located in the front edge of the shoe lift are molded and made permanent. 70 In order to secure the rear end of the lift to the permanent portion of the shoe heel, I employ the fastener illustrated in Fig. 7, which is composed of a sharpened prong 18 and a longer sharpened prong 19. The 75 sharpened prong 19 is provided with serrated or toothed edges 20. The prongs 18 and 19 are connected together by the portion 21, which is transversely curved to fit the rear edge of the heel and the lift. The 80 fastener just described to secure the rear end of the lift is made removable, and the lift itself is designed to receive the prong 19 of this fastener. In the manufacture of the lift a horizontal slot or recess 22 is 85 formed in the rear portion of the lift and a vertical slot 23 is also formed on the inside face of the lift. The slots formed to receive the fastener for the rear portion 90 of the lift are practically T-shaped and in applying the prong 19 is inserted in the slot 22 and the slot 23 will permit a slight giving of the material so that the completed prong may be driven home, the serrated edge 20 acting as a means to prevent 100 the fastener from working loose.

Of course, it is understood when the prong 19 is driven home in the lift, the sharpened prong 18 is driven home in the permanent portion of the heel. In the application of 105 the lift to the permanent portion of the heel, the prongs 14 are first driven into the front edge of the permanent portion of the heel, and after the front portion of the lift is secured, the fastener for the rear portion of 110

the lift is applied as previously described. The fasteners for both the front and rear portions of the lift are made of thin metal preferably light sheet steel and may be stamped of sheet metal. By means of the improvement previously described, the lift may be readily applied and removed.

It will be further observed that the fasteners located on the front edge of the heel point in an opposite direction to the fastener located on the rear portion of the heel.

Having fully described my invention, what I claim is:

1. A shoe heel lift formed of rubber or analogous material, a pair of hook fasteners having anchor holes permanently imbedded in the front edge of the lift, each of which fasteners has a sharpened prong removed from and parallel with the inner face of the lift, said lift being provided in its rear edge with a T-shaped recess, and a detachable fastener having two prongs one of which is provided with a serrated edge located in said recess and the other sharpened and removed from the paralleling the inner face of the lift.

2. A shoe heel lift formed of rubber or analogous material, a pair of fasteners having anchor holes permanently imbedded in the front edge of the lift between the inner and lower faces thereof, each of which fasteners having a sharpened prong removed from and parallel with the inner face of

the lift, the lower prong thereof being about one-half the length of the upper prong, said lift being provided in its rear edge below the inner face thereof with a T-shaped recess, and a detachable fastener having two prongs one of its prongs having its edges provided with a serrated portion located in said recess and with a sharpened prong about half the length of the first mentioned prong removed from and paralleling the inner face of the lift.

3. A shoe lift formed of rubber or analogous material, a pair of hook fasteners having anchor holes permanently embedded in the front edge of the lift and between the upper and lower faces thereof, said fasteners being spaced apart and having a sharpened prong above and parallel with the inner face of the lift, the lower prong being wedge-shaped, said lift being provided in its rear end with a T-shaped recess, said recess extending toward the center of the lift, and a detachable fastener having a pair of parallel pointed prongs, one of said prongs being longer than the other, and having a portion of its edges serrated, said serrated portion adapted to be inserted within the recess for retaining the prong within the lift.

In testimony whereof, I have signed my name to this specification.

JOHN P. REILY.
